UNITED STATES PATENT OFFICE.

WILLIS BENNER, OF NEW YORK, N. Y.

LAMP.

SPECIFICATION forming part of Letters Patent No. 439,995, dated November 4, 1890.

Application filed February 13, 1890. Serial No. 340,309. (No model.)

To all whom it may concern:

Be it known that I, WILLIS BENNER, of New York city, in the county of New York, and in the State of New York, have invented certain 5 new and useful Improvements in Lamps; and I do hereby declare that the following is a full, clear, and exact description thereof, reference being had to the accompanying drawings, in which—

- 10 Figure 1 shows a perspective view of my improved lamp; Fig. 2, a view of a vertical section on line $\alpha\alpha$ of Fig. 1; Fig. 3, a detail perspective view showing the catch for locking the handle attached to the rock-shaft; Fig. 4, a perspective view showing the casing-top carrying the chimney and shade-supports raised from the casing and lamp-body as when the latter is to be lifted from the casing; Fig. 5, a detail perspective view showing a 15 portion of the removable casing-top provided with a flange to fit within the upper end of the casing; Fig. 6, a detail view, in side elevation, of a modified form of means for raising and lowering the lamp-body; and Fig. 7, a transverse vertical section showing the manner of applying my invention to a lamp having a different form of casing from that shown in Figs. 1 and 2.
- 20 Letters of like name and kind refer to like parts in each of the figures.
- 25 The object of my invention is to provide an improved lamp; and to this end my invention consists in the lamp and in the construction, arrangement, and combination of the parts thereof, as hereinafter specified.

30 While I have shown and shall describe my invention as applied to the well-known Rochester lamp, I desire it to be understood that my invention or parts thereof can be equally well applied to or used in connection with other kinds of lamps.

35 In my United States patent, No. 407,153, I show and describe a lamp in which the movable lamp-body is arranged within a casing which has a door in its side through which the said body when lowered can be removed.

40 In the present case my invention is shown as applied to a lamp in which the casing is without the side door, and the lamp-body is 45 to be made removable through the top or upper end of the casing. This arrangement is

found desirable in some forms of lamps where the configuration or ornamentation of the casing will not admit of the presence of a door in the casing side.

55

With the lamp arranged as shown and described in the present application it will be seen that the exterior casing can be made more symmetrical, is capable of better ornamentation, and can be more varied in its 60 shape or configuration than the casing shown on my patented lamp.

In the drawings, A designates the exterior casing, which, while shown in Fig. 1 as substantially cylindrical, can be varied indefinitely in shape, as desired, without departure from my invention. It can also be made of any suitable material. While it appears in Fig. 1 as a closed sided cylinder, such a construction is not necessary. For the sake of 65 ornamentation or to secure lightness portions of the casing can be cut away or removed to any desired extent, provided, however, that enough of the casing material is left to properly support the parts of the lamp and guide 70 and steady the movable lamp-body B. Such body is, like that shown in my said patent, made movable up and down within the casing A, and carries with it the burner B', which has the general appearance and construction 75 80 of that on the well-known Rochester lamp, except in one essential particular.

Instead of having the annular chimney holder or support C fastened to or made in one piece with the perforated cylinder D, 85 which surrounds the wick-tube E, I separate the chimney-holder from such cylinder, so that the burner can move with the lamp-body as the latter is raised and lowered, while the chimney-holder remains stationary. Such 90 holder C is of the ordinary shape, and consists of a ring having the upwardly-extending flange C' around its inner edge and the upright spring-fingers C² C² C² for receiving and embracing the base of the chimney F. I do 95 not, however, desire to limit myself to such construction.

For supporting the ring from the casing A, I provide several upwardly and inwardly extending arms G G, having their upper ends 100 attached to said ring and their outer and lower ends connected with a piece H, which

rests upon the top of casing A. For steady-
ing and holding this piece H in place I pro-
vide it either with arms H' H' H' or with a
flange (see Fig. 5) adapted to project down
5 within, or, as indicated in dotted lines in Fig.
4, outside of the casing.

Instead of having the upwardly-extending
arms G G G for carrying the annular chim-
ney-holder C, I contemplate, where it is de-
sired, forming the piece H with an upwardly-
extending hood, as indicated in dotted lines
10 in Figs. 2 and 3, which would hide the top of
the lamp-body, and to the upper end of which
the ring forming the chimney-holder would
be attached. An opening or openings could
15 be made in such hood to admit the passage
of the usual wick-raising arm I when the
lamp-body was raised and of a match or
lighter to light the lamp. On the upper end
20 of the perforated cylinder D, surrounding the
wick-tube of the burner, is an annular flange
or collar d, which, when the lamp-body is
raised, projects up within the chimney-holder
C. The same steadyng and guiding connec-
25 tion between the burner and the chimney-
holder can obviously be obtained by invert-
ing the arrangement described and providing
the holder itself with a flange or collar to en-
gage the inner or outer side of the upper end
30 of the perforated cylinder.

The shade-receiver K shown is of the ordi-
nary and well-known form, with a ring to en-
gage and be held by the chimney-support, and
35 the usual radiating arms K' K' K'. It can
be so made as to be detachable from the chim-
ney-holder, or, if desired, the arms K' K' K'
can be rigidly secured to such holder or be
formed of continuations of the arms H' H' H'.
40 Either of the constructions described can be
used without departure from my invention.

For the purpose of guiding the lamp-body
as it is moved up and down and steadyng it
in place when it is raised, guides L L L to en-
45 gage the inner wall of the casing A are formed
on or attached to the body sides.

For raising and lowering the lamp-body I
make use of a device similar in some respects
to the one used in my lamp shown and de-
scribed in my said patent—that is, I still
50 have the rock-shaft M with an arm M' there-
on, while the means for securing the locking
of the shaft when it has been turned to raise
the lamp-body is quite different from that
shown in the patented lamp. I now pivot or
55 journal the shaft in the casing or on some
support, so that it will be capable of a longi-
tudinal as well as rocking movement. At
one end it projects out through the casing,
and is provided with a head or handle N by
60 which it can be rotated.

In the form of lamp shown in Figs. 1, 2,
and 3 one of the handles for lifting and car-
rying the lamp is attached to the shaft end
and utilized as the means for turning and se-
curing the locking of the shaft. On the lamp-
65 casing A is a notched lug O, having its notch
o so arranged that a portion of the handle N

will engage the same when the shaft has been
turned to bring the arm M' and the attached
handle upright and has then been moved
70 longitudinally inward. Around the shaft,
within the casing A, is a spiral spring P,
which, pressing at one end against the cas-
ing and at the other engaging the arm M',
75 tends to force the shaft longitudinally in-
ward and hold it as so moved. The side of
lug O, which the handle N first strikes as it
is turned upward, is provided with an in-
clined surface o', as shown, over which the
engaging part of the handle rides until it
80 reaches the notch o. On the further side of
such notch the lug has a projecting arm o'',
which acts as a stop to limit the movement
of the handle and prevent its being swng
85 too far over past the notch. With the con-
struction shown and described the handle at-
tached to the shaft will, because of the fore-
ing inward of the latter by the spring P, be
held securely in engagement with its locking-
notch until it is grasped and drawn outward
90 against the stress of the spring.

In Fig. 6 is shown a modification of my
lamp-body moving and locking mechanism,
in which, instead of having the arm M' en-
gage the lamp-body directly, I connect pivot-
95 ally with such arm a connecting-rod R, which
at its upper end is adapted to engage the bot-
tom of the lamp-body. Such rod can be
guided in its movements by a suitable guid-
ing-opening S in a cross-bar or piece S', at-
100 tached to the lamp-casing, and can have its
upper end provided with a head or cross-
piece R' to engage the bottom of the lamp-
body. The outer end of the shaft is shown
as provided with a suitable turning-head,
105 which, like handle N on the shaft in the form
of lamp hereinbefore described, has a lug or
portion to engage a locking-notch o when the
shaft has been rotated to cause raising of the
lamp-body, and then moved longitudinally
110 inward by the stress of the spring P.

The modification just described is for use
particularly where the casing is a long one,
or for some reason it is preferable or neces-
sary that the shaft M be placed at some dis-
tance below the lamp-body.

In Fig. 7 I show the manner of applying
my invention to a lamp having a casing which
is not cylindrical in general form. To pro-
vide means for guiding and steadyng the
120 lamp-body, the interior of the casing is then
provided with an inner piece T, adapted to
be engaged by the lamp-body or guides there-
on. Such piece can consist of a cylinder sur-
rounding the lamp-body and engaging verti-
125 cal guide-ribs on the outer side of the latter;
or without departure from my invention the
casing or the inner cylinder can be provided
within with several guide-arms to engage the
lamp-body directly.

The operation or manner of using my lamp,
as hereinbefore described and shown in the
drawings, is briefly as follows: When the
lamp is to be lighted, the handle or head on

the shaft M is drawn outward against the stress of spring P, and having been disengaged from the holding-notch is turned so as to rotate the shaft and swing the arm M' thereon downward. By the descent of this 5 arm the lamp-body is lowered within the casing, so that the burner can be readily reached for lighting without the necessity of any removing or touching of the chimney-holder, 10 chimney, or shade. When the lamp is lighted, there is no danger of smoking the chimney, even if the lamp-body be left down for a while, as it has been found that the inward and upward draft of air flowing in at the bottom 15 of the chimney is sufficient to direct the flame inward away from the edges or inner side of the chimney-holder. When the lamp has been lighted, the shaft M is, by means of the head or handle N thereon, turned to 20 swing the arm M' upward, so as to carry the lamp-body B to its elevated position again, with the collar or flange d on the perforated cylinder D of the burner projecting up within the chimney-holder and fitting within the 25 latter, so that the air reaching the burner from outside the wick-tube must pass, as is desirable in the form of burner used through the perforations in said cylinder D. As the arm M' is brought by the rotation of the 30 shaft M into its upright position, the notch-engaging portion of the head or handle N rides over the incline o' on the lug O, so as to force the shaft longitudinally outward against the stress of the spring, and then after it leaves 35 such incline it is at once carried into the locking-notch o by the spring drawing the shaft inward again. If it is desired to remove the lamp-body from the casing—as for filling, emptying, or cleaning it—the piece H, carrying 40 or supporting the chimney-holder and shade-support, can be readily lifted from the casing and set to one side without the necessity of any handling or disturbing of the chimney or shade. When the lamp-body is put 45 back within the casing, the piece H can be readily set in place on the casing-top and the lamp will be immediately ready for use.

My arrangement and construction of lamps whereby all handling or touching of the chimney and shade is rendered unnecessary when the burner is to be lighted or the wick trimmed have been found to be very advantageous, as preventing all danger of smoking, soiling, or breaking the chimney, or of injury to the 55 shade consequent upon the removal and replacing of the latter, necessary in the ordinary form of lamp, whenever it is to be lighted or trimmed.

As indicated hereinbefore, the arrangement 60 of my lamp, whereby the lamp-body can be removed through the top of the casing instead of through a side door, is advantageous, in that it allows the lamp to be made more symmetrical and the lamp-casing to be varied in shape 65 indefinitely and ornamented as extensively as may be desired.

Where the lamp-body used has a burner without the perforated cylinder D surrounding the wick-tube, the chimney-holding ring can, where such is desirable, be provided with 70 a perforated annular piece, as indicated by dotted lines in Fig. 4, up within which the wick-tube will project when the lamp-body is raised. I prefer, however, the perforated cylinder arranged as described and shown here- 75 inbefore, as it is more convenient, and with it there is no danger of smoking the chimney or chimney-holder when the lamp-body is down and the wick is being lighted, as there is where a perforated inner ring on the chimney- 80 holder is used.

While I show and describe the flange or collar on the upper end of the perforated cylinder D, I do not consider the same necessary to secure a good working of the parts of the 85 lamp. It can be dispensed with and the cylinder end can be simply arranged to abut against or be flush with part of the chimney- holder ring.

Having thus described my invention, what 90 I claim is—

1. A lamp having the casing or support, the lamp-body, and the removable top piece above the lamp-body separate from the latter and supported from the casing, substantially as 95 and for the purpose specified.

2. A lamp having the casing or support, the lamp-body, and the removable piece supported on the casing made separable from the body and carrying the chimney-holder, substan- 100 tially as and for the purpose shown.

3. A lamp having the casing or support, the lamp-body, and the top piece removable entirely from said parts and carrying the chimney and shade holders, substantially as and 105 for the purpose set forth.

4. A lamp having the casing or support, the lamp-body, and the removable top piece resting on said casing, so as to be supported thereby, and made movable with reference to 110 said body and carrying the chimney and shade holders, substantially as and for the purpose specified.

5. A lamp having the casing or support, the lamp-body within and supported by the same, 115 and the removable top on the casing, consisting of a piece resting upon the casing and provided with means for holding it in place thereon, substantially as and for the purpose described.

6. A lamp having the casing or support, the lamp-body, and the movable top piece on the upper end of the casing carrying the chimney-holder and provided with a downwardly-projecting portion or portions to engage the 125 casing sides, substantially as and for the purpose specified.

7. A lamp having the lamp-body, a casing or support therefor, and a removable top piece consisting of a ring resting upon the 130 casing and having downwardly-projecting portions to engage the casing sides, and up-

wardly-projecting arms to which the chimney-holder is attached, substantially as and for the purpose shown.

8. In a lamp, in combination with the casing and the movable lamp-body within the same carrying the burner, the perforated outer ring or cylinder surrounding the wick-tube of the burner, and the chimney-holder removably supported from the casing, substantially as and for the purpose set forth.

9. In a lamp, in combination with the casing and the chimney-holding ring, the removable top piece on the casing carrying such ring, the movable lamp-body within the casing having the burner provided with a suitable wick-tube, and the upright perforated cylinder surrounding such tube having the collar or flange to fit within the ring of the chimney-holder when the lamp is raised within the casing, substantially as and for the purpose specified.

10. In a lamp, in combination with the casing, the movable lamp-body within the same carrying the burner and the upright perforated outer ring or cylinder, means for raising the lamp-body and locking it as raised, and the removable annular chimney-support adapted to fit the upper end of such cylinder, substantially as and for the purpose shown.

11. In a lamp, in combination with the casing or support, the movable lamp-body, the rock-shaft journaled so as to be capable of longitudinal motion, means connected with the shaft for engaging the lamp-body and raising the same as the shaft is turned, a spring acting to move the shaft longitudinally, and engaging locking devices on the casing and shaft adapted to be held in engagement by the action of the spring upon the shaft, substantially as and for the purpose set forth.

12. In a lamp, in combination with the casing or support and the movable lamp-body, the rocking and longitudinally-movable shaft on the casing or support, an arm on the shaft to move the lamp-body, a spring acting to

move the shaft longitudinally, a turning handle or head on the shaft for turning the same, and engaging locking devices on such handle, and the casing, substantially as and for the purpose described.

13. In a lamp, the means for raising the lamp-body and locking it as raised, consisting of the longitudinally-movable rock-shaft on a suitable support and having an arm to engage or be connected with the lamp-body, the spring surrounding the shaft and acting to move the same longitudinally, a turning-handle on the shaft, and a locking device on the shaft-support in the path of a portion of the turning-handle when the shaft has been moved longitudinally by the spring, substantially as and for the purpose specified.

14. In a lamp, the means for raising a movable lamp-body and locking the same as raised, consisting of a longitudinally-movable shaft having an eccentric-arm, the spring drawing the shaft longitudinally inward, the support for the shaft provided with a locking-notch, and the handle on the shaft having a portion to engage such notch when the shaft has been turned to raise the lamp-body and is moved inward by the spring, substantially as and for the purpose shown.

15. In a lamp, in combination with the casing or support and the movable lamp-body, the longitudinally-movable rock-shaft provided with means for raising the lamp-body as the shaft is rocked, a spring drawing the shaft longitudinally inward, the lug on the casing provided with the notch and the outwardly-inclined face, a turning arm or handle on the shaft provided with a portion to engage the lug-notch, substantially as and for the purpose set forth.

In testimony that I claim the foregoing I have hereunto set my hand this 1st day of February, 1890.

WILLIS BENNER.
